UNITED STATES PATENT OFFICE

111,922

DESIGN FOR A DRESS

Philip Schlessel, New York, N. Y.

Application July 30, 1938, Serial No. 78,993

Term of patent 3½ years

To all whom it may concern:

Be it known that I, Philip Schlessel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the round necked surplice dress disclosed of the overlapping front and rear skirt portions, as shown.

I claim:

The ornamental design for a dress, substantially as shown and described.

PHILIP SCHLESSEL.
